PORTABLE ELECTRIC LAMP GUARD PROVIDED WITH A PIVOTED DOOR

Filed March 9, 1949

UNITED STATES PATENT OFFICE

2,580,359

PORTABLE ELECTRIC LAMP GUARD
PROVIDED WITH A PIVOTED DOORHector E. Moineau, Marlborough, Mass., assignor
to Marlboro Wire Goods Company, Marlbor-
ough, Mass., a corporation of Massachusetts

Application March 9, 1949, Serial No. 80,365

2 Claims. (Cl. 240—54)

1

This invention relates to lamp guards for trouble lights, such as are used by mechanics and craftsmen. These trouble lights have an extension cord, with an insulating handle equipped with a lamp socket for an incandescent lamp bulb and may be moved from place to place to illuminate the work to be performed. To protect the bulbs of these lamps from breakage by engagement with extraneous objects, a wire cage loosely embracing and enclosing the lamp is mounted on the handle by means of a two part clamp to which the wires of the cage are welded. It is common to permanently affix to the exterior of one side of the wire cage an opaque shield which protects the eyes of the workman from direct glare of the lamp and also serves the purpose of a reflector.

With these constructions it is necessary, when a change of the bulb is required, to entirely remove the clamp from the handle by unscrewing the clamp screws which hold it in place thereon. After the clamp is released from the handle, it, together with the cage affixed thereto, must be entirely removed in order that access may be had to the bulb. After the old or broken bulb has been removed and replaced by a new one, the cage is replaced by reversing the operations stated. The breakage of bulbs in lamps of this character is a frequent occurrence and it is a nuisance to have to entirely remove the cage and its clamp from the handle in order to change the bulb.

The object of the present invention is to provide a novel and economical cage construction whereby the bulb may be changed in a simple and expeditious manner and without the necessity of removing the cage from the handle or releasing the clamp.

I accomplish this result by mounting a wire cage upon the handle, preferably by the use of a clamp as heretofore, but the wire cage is so constituted that a door may be opened in its side to permit the removal or replacement of a bulb without removing the cage from the handle. The shield, heretofore permanently affixed to the exterior of a cage entirely surrounding the lamp bulb, may be utilized, according to this invention, as the door and the longitudinal wires of the cage, conventionally abutting the inner surface of the shield, are omitted to provide the door opening through which the lamp bulb may be inserted into or removed from the cage when the door is open. With this arrangement, the changing of a bulb may be expeditiously performed and yet the structure has all the ad-

vantages of the widely used conventional trouble light of prior practice.

Features of the invention, other than those adverted to, will be apparent from the herein-
5 after detailed description and appended claims when read in conjunction with the accompanying drawing.

The accompanying drawing illustrates one practical embodiment of the invention, but the
10 construction therein shown is to be understood as illustrative only, and not as defining the limits of the invention.

Figure 1 is a perspective view showing a trouble
15 light embodying this invention, with the door
detached to provide in the side of the cage the
opening through which the bulb may be introduced into or removed from the socket of the
handle.

Figure 2 is a vertical transverse section through
20 the cage and shield. This view shows the door
closed and locked in full lines, while the dotted
line position illustrates the door released and
partly removed from the cage.

Figure 3 is a top plan view of the cage with
25 the door removed.

In the drawings, 1 designates a handle, pro-
vided at its upper end with a lamp socket (not
2. An appropriate electrical cable passes into
30 the lower end of the handle and is connected
to the socket in the conventional way. The
handle is preferably made of rubber or other in-
sulating material in accordance with usual
practice.

35 The upper end portion of the handle is em-
braced by a clamp 3 consisting of two semi-
cylindrical sections secured to one another by
bolts 4 which mount the clamp sections firmly
40 on the handle. A wire cage is supported on the
clamp 3. This cage comprises a series of upright,
longitudinal wires 5, secured intermediate their
ends to a horizontal spacing and reinforcing ring
5 by welding or otherwise. The lower ends of the
45 wires 5 are welded to the clamp sections 3,
while their upper ends are similarly secured to
a wire ring 8 by welding or otherwise.

For a little more than half way around the
50 cage in a horizontal direction, the upright wires
5 are spaced relatively close together, so that
the bulb 2 may be adequately protected against
damage by contact with extraneous objects.
However, for the remainder of the distance
around the cage, the longitudinal wires are
55 omitted to provide the cage with a lateral door

opening sufficiently wide to permit the bulb 2 to be passed therethrough into or out of the cage. This opening is adapted to be normally closed by a door 9. I may, if desired, make this door in the form of a wire frame, but I prefer to use a shield, similar to the conventional shield, for this purpose. In accordance with this invention, however, the shield is of a size and shape to close the door opening of the cage and is preferably pivotably secured at its top to the cage. This pivotal connection may permanently attach the shield to the frame. However, I prefer to provide it in its upper portion with a perforation 10 adapted to be detachably engaged with a hook 11 formed on a plate 12 welded across the upper surface of the ring 8. At that portion of the shield, contiguous to the reinforcing ring 6, the shield is provided with an external bead forming an interior channel 13 adapted to register with and seat against that portion of the ring 6 which extends across the door opening. Near its lower edge, said shield is provided with an internal bead forming an external channel 14 and each of the longitudinal wires 5 of the cage are provided at a corresponding elevation with depressions or offsets 15 in the same horizontal plane as the external channel 14 of the shield.

In Figure 1, the shield, i. e., the door, is shown as separated from the cage. When the parts are in this condition, the bulb 2 may be readily passed into or removed from the cage through the side opening beneath the ring 6. Under normal conditions, however, the parts are assembled as shown in Figure 2. To accomplish this, the shield is brought into position to pivotably engage the perforation 10 of the shield with the hook 11. This may be readily accomplished by bringing the shield into the dotted line position shown in Figure 2. The shield is then pivotably swung inwardly into the full line position of Figure 2 to cause the internal channel 13 of the shield to seat against the underlying portion of the reinforcing ring 6. A retainer, in the form of a ring 16, is then moved upwardly over the handle and into engagement with the external channel 14 of the shield and the depressions 15 of the wires 5, which collectively form a seat for said ring. The wires 5 are slightly resilient and the retainer 16 is made of such size that it is adapted to be sprung into engagement with said seat to place the upright wires 5 under a sufficient stress to effectually hold the ring from being inadvertently dislodged.

When the parts are fully assembled, they appear as shown in Figure 2, wherein the shield is resiliently held in place upon the cage, with the lamp bulb safely housed within the resulting structure. Whenever it is necessary to change the bulb this may be readily accomplished by merely springing the retaining ring 16 from its seat so that it may fall over the handle into the position of Figure 1 and thereby release the shield for ready removal.

In the accompanying drawing, the wires 5 are attached to the handle by means of a two part clamp. If desired, the lower ends of these wires 5 may be secured permanently to the handle, as by molding them into the handle or otherwise fixedly attaching them thereto, without departing from this invention. It is preferred that the usual hook 17 be fixed to the plate 12, so that a trouble light may be hung from a suitable support.

The foregoing detailed description sets forth the invention in its preferred practical form,

but the invention is to be understood as fully commensurate with the appended claims.

Having thus fully described the invention, what I claim as new and desire to secure by Letters Patent is:

1. A trouble light comprising: a handle having a socket to receive an electric lamp bulb, a wire cage mounted upon the handle and embodying wires extending longitudinally of the axis of the bulb and also a reinforcing ring extending cross-axially around and secured to the several longitudinally extending wires to space them apart and reinforce them, the majority of said longitudinally extending wires being annularly spaced apart a distance appreciably less than the diameter of the bulb but there being a door space left between two adjacent longitudinally extending wires sufficiently great to permit the passage of the lamp bulb therethrough, and a door for normally closing said door space, said door embodying an interiorly concave shield with a pivotal connection to the end of the wire cage remote from the handle and an external channel near its end adjacent the handle, and a retaining ring cross-axially embracing both the wire cage and the shield and detachably engaged with said channel and with the longitudinally extending wires of the cage to normally hold the shield in closed position.
2. A trouble light comprising: a handle having a socket to receive an electric lamp bulb, a wire cage mounted upon the handle and embodying wires extending longitudinally of the axis of the bulb and also a reinforcing ring extending cross-axially around and secured to the several longitudinally extending wires to space them apart and reinforce them, the majority of said longitudinally extending wires being annularly spaced apart a distance appreciably less than the diameter of the bulb but there being a door space left between two adjacent longitudinally extending wires sufficiently great to permit the passage of the lamp bulb therethrough, and a door for normally closing said door space, said door embodying an interiorly concave shield, with a pivotal connection to the end of the wire cage remote from the handle and provided with an arcuate internal channel seating over that portion of the reinforcing ring which extends across the door space and also having an external channel near its end adjacent the handle, and a retaining ring cross-axially embracing both the shield and the wire cage and detachably engaged with said external channel and with the longitudinally extending wires of the wire cage to normally hold the shield in closed position, the longitudinally extending wires of the cage being provided with depressions in which the retaining ring seats when the latter is in engagement with the external channel of the shield.

HECTOR E. MOINEAU.
